BRAKE ANCHOR

Filed June 14, 1927

FIG. - 1

John Sneed Inventor

By Peter Madeline Golnick & Teare

Attorneys

Patented Aug. 27, 1929.

1,726,046

UNITED STATES PATENT OFFICE.

JOHN SNEED, OF DETROIT, MICHIGAN, ASSIGNOR TO THE MIDLAND STEEL PRODUCTS COMPANY, OF CLEVELAND, OHIO, A CORPORATION OF OHIO.

BRAKE ANCHOR.

Application filed June 14, 1927. Serial No. 198,760.

This invention relates to brakes and more particularly to a mounting or anchorage for the brake shoe.

It is among the objects of my invention to provide a brake shoe which is designed to take advantage of the wrapping effect conferred upon the shoe by the drum and to take equal advantage of this wrapping effect regardless of the direction of rotation of the drum.

Another object is to provide a mounting for brake shoes by means of which a circumferential force delivered to the shoe is transferred to a radial force which forces the shoe directly against the friction surface of the drum.

Another object is to mount the shoe in a simple manner which will involve as few parts as possible and which is consistent with the design of a shoe which can be cheaply made and quickly assembled. A further object is to provide a shoe which can be fitted to a brake drum with a free clearance but which will give a uniform and satisfactory operation without regard to wear or increase in clearance during the life of the brake.

A further object is to mount and anchor the shoe so that radial pressure is maintained between the shoe and the drum not only between the anchoring means and the expanding device, but also at points near the anchoring means and particularly at points beyond the anchoring means relative to the wrapping portion of the shoe.

A further object is to mount the shoe so that the whole of the shoe will be used in the brake engagement and particularly that portion of the shoe which is ordinarily subjected to an unwrapping effect.

Other objects will appear from the following description of the apparatus constituting my invention; the essential characteristics are summarized in the claims.

In the drawings Fig. 1 is an elevation of the shoe mounted within a suitable drum; Fig. 2 is a section taken on lines 2-2 in Fig. 1; Fig. 3 is a modified form of the mounting shown in Figs. 1 and 2.

In carrying out the objects of my invention, I show a suitable brake drum 1 in which is mounted a shoe 2. Suitable expanding means such as a toggle 3, having actuating connections, not shown, is provided to spread the ends of the shoe. The arms of the toggle 55 may be universally connected with the shoe

as at 4. In my preferred form, I use a shoe which is substantially annular having suitable brake lining 5. The shoe is reinforced at its ends as at 10 by suitable channel structure, and has flexible portions 11 arranged between the ends and the mid-portion. The mid-portion of the shoe may be channeled or otherwise suitably reinforced as at 12 and in my preferred form occupy substantially 120° of the shoe. The portion of the shoe 60 12 has, of course, a lining supporting portion 13 and upstanding flanges 15 in Fig. 2. In the center of the flanges 15, a pair of aligned vertical slots 16 are provided and in the same portion of the shoe the enlarged 65 circumferential slots 17 are provided.

Referring particularly to Fig. 2, an anchor pin 20 is mounted in a suitable bracket 21 secured to the usual backing plate 22 so that the anchor pin extends through the channel 70 portions of the shoe through the slots 17. The shoe is entirely out of contact with the anchor pin by reason of the radial dimension 75 of the slot being greater than the diameter of the pin. In this manner, both the circumferential and radial movement of the shoe is permitted without contact with the anchor pin.

Pivottally mounted on the anchor pin, I show a double armed member 30 having 80 arms 31 extending circumferentially away from the anchor pin. These arms are held in contact with the inner side of the lining supporting portion of the shoe by suitable 85 springs 32. These springs may be connected with the tops of the flanges 15 and to the arms of the member 30. A conventional retractor spring 35 is provided across the free ends of the shoe. Suitable stop members 36 are shown adjacent portions of the 90 shoe which have an arcuate surface concentric with the drum, so that the whole shoe may be moved circumferentially when the ends of the shoe are spread, until the 95 movement is terminated by reason of the 100 rocking of the member 30 and the engagement of the mid-portion of the shoe with the drum. The member 30 carries a pin 40 which, in my preferred form, is disposed directly above the pin 12 and in radial alignment 105 therewith. The pin 40 is fixed to the member 30 by a suitable pin 41. The pin 40 extends through the opening 16 and is in contact with the lateral edges thereof, but is given a radial clearing so that the member 110

30 may rock about the pin 20 as an axis within the limits determined by the clearance of the mid-portion of the shoe from the drum without bringing the pin 40 into contact with the upper or lower edges of the slots 16.

In the modified form of my invention shown in Fig. 3, the anchor pin 20^A has ample clearance in the slot 17^A. A link 30^A is 10 pivoted on the anchor pin in a manner similar to the connection of the member 30 to the pin 20 as shown in Fig. 2. The link 30^A carries a pin 40^A pivotally connected to the shoe in aligned opening 16^A in which the pin 40^A 15 closely fits; when the link 30^A is rocked, the body of the shoe is drawn radially outward as it is moved circumferentially.

In operation, considering the drum to be 20 rotated in a clock-wise direction as shown in Fig. 1, the ends of the shoe are spread by the 25 expansion device until there is a slight engagement between the frictional surface and the drum. Upon engagement of the shoe with the drum the whole shoe is tended to be 30 rotated with the drum in a clock-wise direction. The drum is free to rotate except for the connection to the anchor pin 20. However, there will be a bodily rotation of the shoe until the member 30 is rocked by reason of the 35 engagement with the pin 40 in the slot 16 until the left arm of the member 30 forces the mid-portion of the shoe directly into engagement with the drum at or about the point A.

In the meantime, by reason of the flexibility 40 of the right portion 11, there will be a wrapping effect between the end of the shoe and the mid-portion of the shoe substantially around the point A. This effect is combined with the radial movement and the radial pressure exerted by the arm of the member 30 at this point. The braking effect is further increased by the outward movement of the other end of the shoe and the direct radial movement of the portion of the shoe near the 45 point A. In this manner it will be seen that the whole shoe is moved into engagement; that a wrapping effect is had for substantially two-thirds of the full length of the shoe and that the whole shoe is used to effect the braking operation. It is obvious that when the 50 shoe is made symmetrical as I have shown, and when the right and left arms of the member 30 are the same length, that an identical operation is had when the rotation of the drum is in the opposite direction. It can be 55 further seen that radial pressure exerted by the end of the arm of the member 30 can be determined by the ratio of the length of the arm to the distance to the centers of the pins 20 and 40 respectively. Any given characteristics can be imparted to a given brake by varying this ratio.

While the foregoing has been a description 60 of a preferred form of my invention, changes 65 within its scope will appear to one skilled

in the art, I do not wish to be limited other than by the claims appended hereto.

I claim:

1. The combination of a brake drum, a 70 brake shoe, an anchor pin, a member pivotally mounted on the anchor pin and adapted to engage the shoe at a point spaced radially inward from the anchor pin, said member having an arm extending circumferentially and adapted to engage the shoe at a point 75 spaced circumferentially from said anchor pin.

2. The combination of a brake drum, a 80 brake shoe, an anchor pin positioned near the friction surface of said shoe, a member pivotally mounted on the anchor pin and adapted to engage the shoe at a point spaced radially inward from the anchor pin said member having an arm extending circumferentially 85 and adapted to engage the shoe at a point spaced circumferentially from said anchor pin.

3. A mounting for a brake shoe including 90 an anchor pin, a member pivotally mounted on said anchor pin to engage the shoe at a point spaced radially inward from said anchor pin, said member having a second point of engagement with the shoe at a point 95 spaced circumferentially from said anchor pin, whereby circumferential movement of the shoe causes a radial movement at the said second point of engagement.

4. The combination of a brake shoe, an 100 anchor pin disposed remote from the ends of said shoe, a member pivotally mounted on said anchor pin to engage the shoe at a point spaced radially inward from said anchor pin, said member having a second point of engagement with the shoe at a point spaced circumferentially from said anchor pin, whereby 105 circumferential movement of the shoe creates a radial pressure at the said second point of engagement.

5. The combination of a brake drum, friction means associated with the drum, means 110 for limiting the circumferential movement of said friction means including a member having a point of contact with said friction means and mounted on a fixed pivot at a point substantially radially without and beyond the said point of contact and exerting a radial pressure on said friction means proportional to and dependent upon the circumferential movement thereof.

6. The combination of a brake drum, a 115 brake shoe disposed within the drum, said shoe having a deepened channel portion, an opening in one of the flanges of said deepened channel portion, an anchor pin extending through said opening and out of contact therewith, a member pivotally mounted on said anchor pin, a pair of aligned slots in the flanges of said channel portion, a second pin carried by said member and extending through said slots and having lateral engagement therewith, said 120 125 130

member having arms extending circumferentially relative to said anchor pin whereby circumferential movement of said shoe rocks said member about the anchor pin and forces 5 one of said arms outwardly and into engagement with said shoe, thereby urging the shoe into engagement with the drum.

7. The combination of a brake drum, a brake shoe disposed within the drum, said shoe having a deepened channel section in the mid-portion thereof, an opening in one of the flanges of said deepened channel portion near the lining supporting portion of the shoe, an anchor pin extending through said opening 10 and out of contact therewith, a member pivotally mounted and said anchor pin disposed between the flanges of the channel portion, a pair of aligned openings in the flanges of said channel portion and located radially inward 15 of said anchor pin, a second pin carried by said member and extending through said opening and in engagement therewith, whereby circumferential movement of said shoe rocks said member about the anchor pin and 20 forces the shoe outwardly and into engagement with the drum.

8. The combination of a brake drum, a brake shoe disposed within the drum, said shoe having a deepened channel section in the 30 mid-portion thereof, an opening in one of the flanges of said deepened channel portion, an anchor pin extending through said opening and out of contact therewith, a member pivotally mounted on said anchor pin disposed between the flanges of the channel portion, a pair of aligned slots in the flanges of said channel portion and located radially inward 35 of said anchor pin, a second pin carried by said member and extending through said slots 40 and having lateral engagement therewith, it being free to move radially thereof, said member having arms extending circumferentially relative to said anchor pin whereby circumferential movement of said shoe rocks said 45 member about the anchor pin and forces one of said arms outwardly and into engagement with said shoe, thereby urging the shoe into engagement with the drum.

9. The combination of a brake drum, a 50 brake shoe disposed within the drum, an anchor pin not engaging the shoe, said shoe having an inwardly extending portion adjacent the anchor pin, a member pivoted about the anchor pin and having a contact with the 55 said inwardly extending portion of said shoe and having a pair of arms extending circumferentially on opposite sides of said anchor pin and either arm adapted to engage the inner face of the shoe and exert a radial force 60 against the inner face of said shoe when the shoe moves circumferentially relative to said anchor pin.

10. The combination of a brake drum, a substantially annular brake shoe disposed 65 within the drum, an anchor pin not engag-

ing the shoe, said shoe having an inwardly extending portion adjacent the anchor pin, a member pivoted about the anchor pin and having a radially sliding contact with the said inwardly extending portion of said shoe 70 and having an arm extending circumferentially of said anchor pin adapted to engage the inner face of the shoe and exert a radial force against the inner face of said shoe when the shoe moves circumferentially relative to 75 said anchor pin.

11. The combination of a brake drum, a shoe, an anchor pin, a member pivotally mounted on said anchor pin and having arms extending in opposite directions circumferentially away from said anchor pin, said member being engaged by said shoe at a point between said anchor pin and the center of the drum whereby the circumferential movement of the shoe in either direction causes one or 80 the other of the arms of the member to exert a radial pressure outwardly against the shoe.

12. The combination of a brake drum, a substantially annular shoe, said shoe being of channel section substantially midway between 90 its ends, an anchor pin disposed near the mid-portion of the shoe, a member pivotally mounted on said anchor pin and having arms extending in opposite directions circumferentially away from said anchor pin, said 95 member being engaged by said shoe at a point between said anchor pin and the center of the drum whereby the circumferential movement of the shoe in either direction causes one or the other of the arms of the member to exert 100 a radial pressure outwardly against the shoe.

13. In combination, a brake drum, a friction device adapted to be expanded into engagement with the drum, an anchor pin disposed near the friction surface of said device, 105 a member pivotally mounted about said anchor pin having a point of engagement with said friction device remote from the frictional surface thereof and having a second point of engagement circumferentially 110 spaced from the first point of engagement whereby circumferential movement of said friction device rotates the member about the anchor pin and directs a radial force between said friction device and said drum near the 115 said second point of engagement of the member with the said friction device.

14. An anchorage for a brake shoe comprising a member mounted on a fixed pivot and engaging the shoe at a point substantially 120 between said pivot and the center of the brake and adapted to force the shoe outwardly in response to circumferential movement thereof.

15. In a brake having a fixed supporting 125 part and a shoe part, an anchorage for the shoe comprising a member pivotally mounted on the supporting part and having points of contact with the shoe spaced substantially a right angle from each other about the pivotal 130

center of said member, one of said points lying in the radial zone of said center whereby one of said points of contact moves substantially radially when the other of said points moves circumferentially.

16. In a brake comprising a shoe part and a relatively fixed supporting part, an anchorage comprising a substantially T-shaped member pivotally mounted on the supporting part, and having an arm engageable with the

shoe and having oppositely extending arms selectively engageable with the shoe depending on the movement of the shoe relative to the fixed supporting part.

17. A mounting for a brake shoe including an anchor pin, a member pivotally mounted on said anchor pin to engage the shoe at a point spaced radially away from said anchor pin, said member having a second point of engagement with the shoe at a point spaced circumferentially from said anchor pin, whereby circumferential movement of the shoe causes a radial movement at the said second point of engagement.

18. In a brake, the combination of a drum, a substantially annular brake shoe having

spaced ends, means engaging said ends for forcing the shoe into engagement with the drum, said shoe having a relatively rigid mid-portion opposite its ends, an anchor pin disposed adjacent said relatively rigid mid-portion and a member pivotally mounted on said anchor pin and engaging the relatively rigid portion of said shoe at a point spaced between the anchor pin and the center of the 35

brake.

19. An anchorage for a friction device adapted to be associated with a brake drum, including a member pivoted about a fixed point and contacting with the friction device 40 in substantially the radial plane of said point and adapted to be rocked about that point by circumferential movement of said friction device, said member having a portion extending circumferentially of the friction device 45 and contacting therewith at a point remote from the fixed point, and adapted to move said friction device radially when said member is rocked.

In testimony whereof, I hereunto affix my 50 signature.

JOHN SNEED.
